UNITED STATES PATENT OFFICE

152,207

DESIGN FOR A PROJECTOR

Otto R. Nemeth, Chicago, Ill.

Application November 18, 1946, Serial No. 134,865

Term of patent 14 years

(Cl. D61—1)

To all whom it may concern:

Be it known that I, Otto R. Nemeth, a citizen of the United States, residing at Chicago, Illinois, have invented a new, original, and ornamental Design for a Projector, of which the following is a specification, reference being had to the accompanying drawings, forming part thereof.

Figure 1 is a perspective view of a projector, showing my new design;

Figure 2 is a rear end elevational view;

Figure 3 is a side elevational view, the opposite side being plain;

Figure 4 is a plan view thereof.

I claim:

The ornamental design for a projector, as shown and described.

OTTO R. NEMETH.
